W. F. BEATTY,
CABINET FOR ICE CREAM AND THE LIKE,
APPLICATION FILED MAR. 19, 1917.

1,358,503.

Patented Nov. 9, 1920.

FIG. 1.

FIG. 2

Inventor:

William F. Beatty
By John Elias Jones,
Attorney.

UNITED STATES PATENT OFFICE.

WILLIAM F. BEATTY, OF CINCINNATI, OHIO.

CABINET FOR ICE-CREAM AND THE LIKE.

1,358,503.

Specification of Letters Patent. Patented Nov. 9, 1920.

Application filed March 19, 1917. Serial No. 155,893.

To all whom it may concern:

Be it known that I, WILLIAM F. BEATTY, a citizen of the United States of America, and a resident of Cincinnati, in the county of 5 Hamilton and State of Ohio, have invented a certain new and useful Improvement in Cabinets for Ice-Cream and the like, of which the following is a specification.

This invention relates to cabinets or refrigerator devices used in containing and serving ice-cream or the like, and for special use in connection with soda-fountains, as well as in the serving-rooms of hotels, restaurants and confectioneries.

15 The structure of the improvement, as well as the many objects that cover the advantages thereof, will be fully described in detail in connection with the accompanying sheet of drawings, in which latter, Figure 1 20 is a vertical cross-section, taken centrally from front to rear showing the device closed with the exception of the partially open lid leading to the ice-packed chamber and the empty can ready for its supply of cream, 25 when its independent orifice and covering-lid have first been thrown open, and Fig. 2 is a perspective view of the device showing it as it appears when entirely closed and ready for use.

30 The casing of the cabinet is composed of a front-wall 1; side-walls 2; back-wall 3; bottom 4; and a top 5, the latter having a sloping fore-portion front 6.

7 indicates short supporting-blocks 35 provided at the four corners of the bottom 4, so as to elevate the latter the desired distance above the floor.

8 indicates a lining or facing of cork or the like provided on the inner faces of the 40 walls 1, 2, 3 and bottom 4 of the casing, as best shown in Fig. 1. This lining is for the usual purpose of insulation, the ice 9, in broken form, being packed within it and to surround the can 10, except its open orifice 45 or mouth, also as best shown in Fig. 1. The cork-lining thus forms an insulated chamber for the ice whereby the cream in the can 10 is kept or preserved in the congealed or frozen state for serving.

50 An auxiliary-partition 11 is provided in the ice-chamber at an inclination so as to leave an air-space 12 beneath its lower face and to support the broken ice above said air-space and thus save in the ice supply 55 which would not be of any benefit in that

part of the box or casing represented by said air-space 12.

The can 10 is placed in the ice-chamber at an inclination and within a jacket 13, the latter shown as contacting at its lower edge 60 with the cork-lining and having its upper edge flanged, as shown at 14 so as to rest in air-tight contact with a shoulder 15 made in the orifice or opening 16 of the sloped front 6 of the casing top.

65 A filling ring or gasket 17 is provided within said orifice 16, its internal diameter corresponding to that of the jacket 13 and its external diameter being practically that of the flange 14, which latter it covers and thus forms an air-tight joint above said flange in the sloping top 6.

70 18 indicates a lid for the said orifice in said sloping top 6. This lid slides or rotates at an inclination downwardly on the pivot 75 bolt or pin 19 toward the server, the said pin passing through the thin portion 20 of the lid after extending outwardly from the lower edge of the said sloped portion 6 of the casing top, as best shown in Fig. 1. A 80 handle 21 is provided on the thick body-portion of the lid 18, diametrically opposite the outer end of the pivot bolt or pin 19 so as to conveniently rotate or rotatably slide said lid to and from covering-position over 85 the entrance to the can 10 and its contents.

86 The jacket 13 forms a convenient receptacle for the can and to provide for the ready insertion or removal thereof, and whereby the ready replacing of filled cans or empty 90 ones may be effected. Suitable beads 10^a are provided at the upper end of can 10 for convenience in drawing it from within the jacket.

95 22 indicates an orifice provided in the rear horizontal portion of the top 5 of the casing or cabinet, independent of the orifice 16 in the sloping fore-portion 6 of the said top 5, and 23 is a lid adapted to fit within the orifice 22, hinged at 24 at its rear edge and 100 provided near its fore edge with a handle 25. The fore edge of lid 23 is sloped, as shown at 26, and the fore edge of the opening 22 being also sloped, to correspond as shown at 27, provides a tight joint at said fore-edge of the lid. Through the orifice 22 the ice or other refrigerating agent or material is placed within the cabinet and suitably packed so as to surround the jacket 13 that 105 contains the ice-cream can. The orifice 22 110

forms a man-hole through which the interior of the cabinet can be packed as well as unpacked and kept clean and otherwise sanitary. The packing and cleaning can be effected in the ice-chamber without opening the lid 18 of the cream-can orifice so that the cream-chamber is protected against the entrance of ice or foreign matter, especially when it is desired to repack the cabinet at any time that there is a supply of cream in the can.

The entrances 16 and 22 to the ice-chamber and to the cream-chamber, respectively are thus entirely independent of each other and the ice is not open or subject to the melting effects of the outer warm atmosphere when its lid 23 is closed and at the time or numerous times that the other lid 18 is open for access to the interior of the cream can 10. These are important features in the use of my invention, and the mounting of the cream-receptacle at an inclination within the ice-chamber enables the server of the cream to have access thereto in a more convenient or natural position, whereby the service of the cream is facilitated and the entrance of the arm, with the serving-implement, in to the cream-can is at an angle forwardly and downwardly from the person so that the cream can be removed at the same angle, which is far better than reaching down into a perpendicular can that is remote from the person and more difficult to reach the cream as well as to remove it.

It will be observed that there will be no lost refrigeration while dispensing the cream in this air-tight cabinet, and also, no interference with the service while packing the ice in the cabinet, the rear orifice 22 being far enough remote from the fore opening leading to the cream-can so that the packing of the ice-chamber can be effected by another person, if desired, while the server of the cream has the lid 18 open, which is important in the speedy service of cream, especially where a number are to be served.

In summing up, it will be seen that the cabinet is a sanitary one; a great saving of ice and other means of refrigeration is possible; a material saving of time in packing is also provided for; an exchange of cans, without removing the cabinet top, can be readily made at any time; and no direct cover is needed on the cream-can itself while packing the ice-chamber, such as is needed in connection with the many kinds of ice-cream cabinets already in use, as the ice in other cabinets is packed in the chamber around the can through the same orifice that access is had to the can, there being no other orifice but that single one in the cabinet to reach the ice-chamber.

To remove the jacket 13 from the cabinet,

it is necessary to open the lid 18 and then withdraw the tight-fitting gasket or ring 17, but that is seldom necessary and practically only when it is desired to clear the ice-chamber entirely of its contents and to get at its entire interior for cleaning or other purpose.

The ice-chamber is drained through the vertical passage-way 28 in the bottom thereof, a plug 29 being used to stop the upper end of said passage-way and adapted to be readily removed from the inside, especially when it is desired to clean the interior of the cabinet, as well as to flush it.

An overflow-spout 30 is provided in one of the side-walls of the cabinet and under control of a suitable valve so as to readily draw off any fluid above its level.

I claim:

An ice-cream cabinet comprising an ice-containing chamber directly surmounted by a single cover or top that partakes of a horizontal rear-portion and a sloping fore-portion, an ice entrance or inlet-supply orifice provided in the said horizontal rear-portion of the cover or top and having a suitable hinged lid, an independent orifice made in the said sloping fore-portion of the cover or top arranged forwardly-adjacent to and aligned with said ice-inlet orifice in the horizontal rear-portion and provided with a suitable swinging or hinged lid, an inclined cylindrical jacket or chamber having a flanged rim and directly embedded in or surrounded by the ice-content of the said ice-containing chamber and removably-supported from the said independent orifice in the sloping fore-portion of the cover or top, and a lidless ice-cream can or receptacle removably inserted and held in the said ice-embedded inclined jacket, the whole being arranged and combined whereby the ice-chamber may be filled with broken or cracked ice to surround or embed the said jacket except its mouth-end while the adjacent orifice leading to the ice-cream can is either open or closed and the ice-cream removed from its container-can while the ice-chamber is either open or closed, or the ice-cream can placed into or replaced from using-position in said supporting and ice-separating jacket in the said ice-containing chamber independent of the ice-chamber and neither the ice-cream can nor the ice-chamber subject to interference with each other beneath the said single cover or top and more especially the ice-cream itself protected from the salt-sprinkled ice-content of the ice-chamber when said ice-content is to be replenished from time to time in the ice-containing-chamber, substantially as herein shown and described.

WILLIAM F. BEATTY.
